AUTOMOBILE LUGGAGE RACK

Frederick L. Duer, 2810 Madison St., Bellwood, Ill.

Filed June 26, 1964, Ser. No. 80,590

Term of patent 14 years

(Cl. D14—27)

I claim:

The ornamental design for an automobile luggage rack, substantially as shown.
